The schedules and drawings which are part of the same To all whom it may concern:

Be it known that I, Elmer J. Sley, of Somerville, in the County of Middlesex, and State of Massachusetts, have originated and designed a new Pattern for Carpets or other Fabrics, of which the following is a full, clear, and exact description, reference being had to the accompanying drawings, making part of this specification.

This pattern when matched is composed of two square blocks divided into four equal parts by bands running at right angles with each other, from center to corners.

These blocks are formed of mottled work interspersed with heavy veins A, B. In the center of each square is a small diamond C. The colors employed for the different parts of the design may be varied to suit the taste or wish of the manufacturer.

Claim
